UNITED STATES PATENT OFFICE.

ALLAN H. MCINTYRE, OF DUNEDIN, FLORIDA, ASSIGNOR TO SKINNER MACHINERY COMPANY, OF DUNEDIN, FLORIDA, A CORPORATION OF FLORIDA.

BIN DOOR.

Application filed February 1, 1922. Serial No. 533,228.

To all whom it may concern:

Be it known that I, ALLAN H. MCINTYRE, a citizen of the United States, residing at Dunedin, in the county of Pinellas and 5 State of Florida, have invented certain new and useful Improvements in Bin Doors, of which the following is a specification.

Bin doors, particularly that type heretofore employed in fruit bins through which 10 the fruit is discharged when desired, have serious objections, the principal one being that the fruit remaining in the bin adjacent the bin opening or door is bruised at the time of opening or closing of the door and in 15 certain cases the opening or closing of the door directs the stream flow of fruit angularly to one side of the door opening.

This invention relates to a bin door adapted for opening and closing without 20 bruising or pinching the fruit and without changing the normal flow direction of the fruit passing through the door opening. The invention consists principally in providing a door for controlling the opening 25 and which operates from beneath the bin, substantially in a vertical plane.

In the drawings, wherein the preferred embodiment of my invention is illustrated—

Fig. 1 is a transverse sectional view of a 30 bin opening with my improved door associated therewith.

Fig. 2 is a view in front elevation of the bin door opening with the door in closed position.

In the embodiment illustrated in the various figures of the drawing, and in each, 35 1 indicates a bin frame mounting a joist or support 2 to which is secured the forward edge of a fabric 3 which is tightly 40 stretched and which forms the bottom of the bin, said fabric being inclined toward the member 2. The front wall 4 of the bin is cut vertically as at 5 forming a door opening 6 of the desired width and which opening 45 is adapted to be closed by a door 7, illustrated as of fabric construction, preferably canvas, of a width corresponding to that of the door opening 6 and of a length slightly greater than the depth thereof. At 50 its upper and lower edges the door 7 is strengthened by the respective bars 8 and 9, the bar 8 being at the upper edge and the ends 10 thereof extending laterally beyond the edges of the door for reception

within recesses or notches 11 in the upper 55 surface of the bin front wall 4 when the door is in closed position.

To the center of the lower edge of the door 7, preferably through the member 9, is secured one end of a tension spring 12, 60 fixed at its opposite end, as at 13, and the tension of which is adapted to maintain the door or curtain 7 taut at all times when either open or closed and to maintain the inner surface thereof in contact with the 65 point 14 of the joist 2.

Illustrated as carried by the joist 2 and extending transversely beneath the door opening 6 with its inner surface spaced from the outer face of the joist 2 is a guide 70 rod 15 within which operates the curtain or door 7. When the curtain is lowered or drawn downwardly by the action of the spring 12, the portions 10 of rod 8 contact with the ends of the guide rod 15 and limit 75 the downward movement of the curtain, and when said curtain is raised or moved to closed position, the guide rod 15 together with the spring 12 precludes the bulging of the curtain to permit the escape of the 80 fruit from the bin.

By this curtain operating in a vertical plane it will be observed that the fruit, either on the opening or closing of the door or curtain, is not forced against any permanent wall as in case of swinging doors, and is, therefore, not bruised or pinched, and it will be observed that during the raising or lowering of the curtain the fruit level above the upper edge 8 thereof enables 85 the fruit to roll thereover into the receptacle positioned beneath the bin opening, and that the opening or closing of the door or curtain does not effect the direction of the stream flow through said door opening during the opening or closing operation.

Having thus described my invention what I claim as new and desire to secure by Letters Patent of the United States is:—

1. In combination with a bin floor, a substantially vertically disposed bin wall rising therefrom and provided with a door opening, a vertically slidable door receivable within said opening for closing the same, a guide at the base of said door opening below 100 the floor through which said door slides, means carried by the door for engaging the door wall for holding the door in closed position.

sition, said means adapted for engaging said guide to limit the opening movement of the door.

2. In combination with a substantially vertically disposed bin wall provided with a door opening, a door of flexible material vertically slidable within said door opening, stiffening rods disposed transversely of the upper and lower edges of the door, the ends 10 of the upper rod projecting beyond the side edges of the door, stops at opposite sides of the upper end of the door opening for receiving said projecting ends to retain the door in closed position, a guide at the lower 15 end of said door opening and through which the door slides and with which said projecting ends contact when the door is in full open position, and a spring secured to the lower edge of the door for retaining the same 20 stretched within the door opening and for lowering the door on the release of said projecting ends from said stops.

3. In combination with a door opening having upwardly extending side walls, a 25 door for closing said opening and comprising a flexible curtain movable vertically in said door opening, a guide at the lower end of said opening and through which said curtain passes when operated, means secured to the lower edge of the curtain for maintaining 30 the same under tension, a rod at the upper edge of the curtain for bracing the same, said rod adapted to engage the walls of said guide and limit the lowering of the curtain, 35 and devices engageable by the rod on the

raising of the curtain to close said door opening for holding the curtain in closed position.

4. A bin having a side wall and a bottom wall inclined downwardly toward said side 40 wall, said side wall provided with a door opening, a door for closing said opening and comprising a flexible curtain movable vertically in said door opening, a guide surface at the lower end of said opening and over 45 which the curtain slides when operated, means secured to the lower edge of the curtain for maintaining the same under tension and for drawing the same angularly and inwardly beneath the bin, a rod at the upper 50 edge of the curtain for bracing the same and for limiting the downward opening movement of the curtain, and devices engageable by the rod on the raising of the curtain for closing said opening and adapted for holding the curtain in closed position.

5. In combination with a bin having a floor and a substantially vertically disposed bin wall rising above the floor and provided with a door opening extending to the floor, a door 60 vertically slidably upwardly into said opening for closing the same, means for maintaining said door in its closed position, said door when opened permitting the bin contents to freely flow over its upper edge from 65 the bin opening.

In testimony whereof I have signed my name to this specification.

ALLAN H. McINTYRE.
